UNITED STATES PATENT OFFICE.

THEODOR WENSEL, OF CHICAGO, ILLINOIS.

BUILT-UP SHAFT OR ROD AND THE LIKE AND METHOD OF PRODUCING SAME.

Application filed June 6, 1927. Serial No. 196,804.

This invention relates to improvements in built up shafts or rods and the like and in the method of producing the same, and it consists of the matters hereinafter described and more particularly pointed out in the appended claims.

The primary object of the invention is to provide a light, strong, built up structure suitable for the shafts of golf clubs, casting 10 rods, and the like, which has the desired springiness or whip and is unaffected by atmospheric changes.

A further object of the invention is to provide a novel method of producing such a structure, which method insures a standard of production wherein the same weight, whip and other characteristics desired are attained in all structures made in accordance with the method.

20 To this end the structure is made of strips of long straight fibrous material such as found in certain woods and in bamboo and these strips are segmental or wedge shaped in cross section, with the grain in each segment extending parallel with one of the longer sides of the segment, which side is disposed radially in the structure. By this radial arrangement of the grains on one side of each segment, there is always assured, in 25 the bending or flexing of the structure, that such bending or flexing will always take place in the plane of the grain edges of oppositely disposed segments, which results in a quick, snappy return to a true straight condition.

30 As an example of one of the embodiments of the invention, I employ or use bamboo which because of its more favorable characteristics readily lends itself to the carrying 40 out of the improved method, but this use is to be considered as illustrative only and not by way of limitation.

In the drawings:

Fig. 1 is a view in elevation of a piece of 45 bamboo, with parts broken away to more clearly show the structure thereof.

Fig. 2 is an end view of the same on an enlarged scale, as when split into halves.

Fig. 3 is an end view of strip after the 50 halves shown in Fig. 2 have been split up into strips of less width.

Fig. 4 is an end view of coacting dies by which the strips shown in Fig. 3 are acted upon to straighten and flatten the same.

Fig. 5 is a view similar to Fig. 4 with one 55 of the strips of Fig. 3 in place therein, before the associated dies have been brought together.

Fig. 6 is a view similar to Fig. 5 after the dies have been brought together to straighten 60 and flatten a strip.

Fig. 7 is an end view on an enlarged scale of a strip after the same has been straightened and flattened.

Fig. 8 is another view of the strip after a 65 further operation has been produced thereon to give it a wedge shaped cross section.

Fig. 9 is an end view of a full complement of such wedge shaped strips, cemented and grouped about a common axis and bound 70 round for setting.

Fig. 10 is an end view of a finished rod after being turned to shape and size.

In order that the method be more clearly understood I will describe the same as 75 when bamboo is employed as the material operated upon to produce the finished built up structure.

Bamboo which is classed as a member of the cane family has a long straight fibrous 80 grain. It comprises a tubular hollow body 1 having annular joints or nodes 2 at certain intervals, the cavity or interior of the stem being closed off by diaphragms 3 at each joint or node. The outer skin 4 of the 85 body, which is often referred to as the "enamel" is dense and more compact in its fibrous arrangement than the inner portion 5 of the body, which is more or less pithy. The fibers or grain of the body are substantially 90 straight from end to end and said body has the characteristic of permitting a splitting or cleaving which follows the fibers or grain.

In carrying out the invention, I take a 95 piece of bamboo 1 of suitable length and remove the nodes 2 therefrom in any suitable manner to provide a smooth uninterrupted exterior surface. The bamboo is then split longitudinally into sections or halves as shown 100 in Fig. 2 after which the transverse wall parts left by the diaphragm portions 3, during this splitting, are removed in any suitable manner to leave a smooth interior surface. By splitting I do not mean "ripping" as with 105 a saw, but I employ a cleaving action wherein the splitting follows the grain so that the fibers are not cut transversely as would hap-

pen in sawing; the latter exposing the fibre ends which I wish to avoid. After the dia-
phragm portions have been removed from the
two halves thus split, I further split each
5 half into the desired number of smaller trape-
zoidal sections 6, one of which is best shown
in Fig. 3. Because of the following of the
grain in splitting, it is apparent that the lat-
eral edges of each section will not be exactly
10 straight or parallel and the inner and outer
surface of each section will be concavo-convex
as is readily apparent.

After thus providing such split sections,
I treat them in a manner making them trans-
15 formable under pressure, which treatment
also renders them waterproof when incor-
porated in the finished article. Either of two
methods of such treatment may be employed
20 with substantially the same advantageous re-
sults and for convenience I have termed them
the "hot or heat" and the "cold" treatments
respectively. Under the hot or heat treat-
ment I prepare a solution of the following in-
25 gredients: 3 oz. amyl acetate, 1 1/4 oz. aniline
oil, 1 1/4 oz. turpentine, 5 oz. wood alcohol.

These ingredients after being well mixed
are allowed to stand from twenty-four to
forty-eight hours. I then mix therewith the
30 desired amount of celluloid in small pieces to
bring the solution to the consistency of a
medium oil; the celluloid pieces going into
solution. This solution is brought to a suit-
able heat in a closed vessel to prevent evapora-
35 tion and the split bamboo strips before men-
tioned are soaked therein for about forty-
eight hours so as to become thoroughly im-
pregnated therewith; after which the im-
pregnated strips are further treated as will
40 later appear.

Under the cold treatment I prepare a solu-
tion of the following ingredients: 8 oz. water,
1/2 oz. bichromate of potash, 1 oz. white glue.

The potash is first dissolved in the water
and the glue then added thereto. When all
45 dissolved the split bamboo strips are placed
therein for about 24 hours and will become
impregnated therewith, after which they are
treated as will further appear.

After the strips have been impregnated
50 with the solution and before drying I sub-
ject each strip to pressure in a suitable die
whereby it is not only flattened, but its lateral
edges are straightened, and its cross sectional
shape is changed to rectangular. In carrying
55 out this step of the process I provide a chan-
nel shaped female die such as best shown in
Fig. 4. This die has an upwardly opening
groove 7 with a flat bottom 8 the sides of said
groove being partly upright and parallel as
60 at 9 and partly upwardly and outwardly di-
verging as at 10 to provide a substantially
wide mouth 11 therefor. 12 indicates the
associated male die which is of a cross section
corresponding to the bottom portion of said
65 groove. I place one of the treated strips in

the female die as shown in Fig. 5, with the
enameled side 4 of said strip (downward)
after which said dies are moved relatively,
the one toward the other. This pushes the
strip into the bottom of the groove the side 70
margins of the strip being therein straight-
ened and the top and bottom surfaces thereof
being flattened out so that the strip takes on
a symmetrical rectangular cross section of a
dimension greater in one direction than the 75
other. This operation also compresses the
fibers of the strip and renders it more dense
or solidified as is best shown in Fig. 6.

After the strip has been thus operated upon,
it is removed from the die as a perfectly 80
straight one, with right angle sides and top
and bottom surfaces as best shown in Fig. 7.
If the strip has been treated under the "cold"
solution before mentioned, it is dried and then
exposed to sunlight for a while. Should it 85
be stained from the potash, it is again washed
and again put under pressure as before which
will reset it. However, this is not necessary
when the strips have been "hot or heat"
treated. As best shown in Fig. 7, the 90
enameled surface 4 now extends parallel with
one of the wider surfaces of the strip.

The next operation is to split the straight-
ened strip in a plane inclined to any one of
95 said surfaces and this plane extends from one
top corner to the opposite bottom corner as in-
dicated by the line 13 in said Fig. 7. I have
thus produced two half strips 14—14^a of a
three sided segmental or wedge shaped cross
100 section and I retain that segmental strip 14
as shown in Fig. 8 which includes the enameled
surface 4 for further operation and dis-
card the other segmental strip 14^a which be-
cause it contains substantially all the un-
105 enameled and pithy part of the bamboo is not
so strong and usable.

I then take the desired number of strips
of segmental cross section and group them
radially about a common axis after applying
a waterproof adhesive to one of the wider sur-
110 faces and then bind this group together as
by wrapping or winding a cord 15 thereon to
hold them in this position until they set hard.
The grouping together is best shown in Fig.
9. It is to be noted from Fig. 9 that when
115 these segmental parts are grouped together
that the enameled portions 4 of all strips ex-
tend radially of the group and that the grain
in each segment does not extend radially but
extends parallel with its own enamel portion.
120 After the group has been set into assembled
shaft form I remove the binding cord and
place the built up blank in a machine and
form a shaft of the desired cross section for
either the shaft of a golf club, a part of a
125 casting rod, a walking stick or any other de-
sirable shape. Such a shaft is easily formed
and does not split or crack and leaves a sur-
face which will take a high finish. Thus I
have a structure which no matter which way 130

it is bent, must bend in the plane of substantially two or more oppositely disposed enameled parts. Thus these enameled parts being more tough than the remaining parts, are so 5 supple and springy as to immediately return to a straight position.

The finished shaft has that whip desired in golf club shafts and casting rods, and it is not only light in weight but is exceedingly 10 strong and water proof so as to insure long service in use.

While in describing my invention I have referred in detail to the arrangement and form of the various parts as well as to the 15 various steps and sequences thereof, the same is only to be considered as by way of illustration only so that I do not wish to be limited thereto except as may be pointed out in the appended claims.

20 I claim as my invention:

1. The method of making a built up shaft or rod and the like which consists in providing a length of straight grained fibrous material, splitting the same with the grain into a 25 plurality of strips, straightening each strip by a confining pressure, making each strip wedge shaped in cross section, applying an adhesive to said wedge shaped strip, and then grouping a full complement of said wedge shaped strips about a common axis to provide 30 said built up shaft or rod.

2. The method of making a built up shaft or rod and the like which consists in providing a length of straight grained fibrous material, splitting the same with the grain into a 35 plurality of strips, straightening each strip by a confining pressure, making each strip wedge shaped in cross section, applying an adhesive to said wedge shaped strips, grouping a full complement of such wedge shaped 40 strips about a common axis to provide a built up shaft or rod and then turning the same to shape.

3. The method of making a built up shaft 45 or rod and the like which consists in providing a length of straight grained fibrous material, splitting the same with the grain into a plurality of strips, impregnating each strip to solidify the same and then straightening each strip by a confining pressure, making 50 each strip wedge shaped in cross section, applying an adhesive to said wedge shaped strips, and then grouping a full complement of said wedge shaped strips about a common 55 axis to provide a built up shaft or rod.

4. The method of making a built up shaft 60 or rod and the like which consists in providing a length of straight grained fibrous material, splitting the same with the grain into a plurality of strips, of substantially rectangular cross section, straightening each strip by a confining action and correcting the 65 rectangular cross section thereof, splitting each rectangular corrected strip along the plane of its diagonally opposite corners to

provide strip parts of a wedge shaped cross section, applying an adhesive to the wedge shaped strips, grouping a full complement of such wedge shaped strips about a common axis to provide said built up shaft or rod and 70 then turning the same to size and shape.

5. The method of making a built up shaft or rod which consists in providing a length of bamboo, removing the nodes therefrom, splitting the same along the grain into strips 75 and removing the diaphragm therefrom, straightening and flattening each strip by a confining pressure, making each strip wedge shaped with the enamel of the bamboo on one of the tapering faces thereof, applying an 80 adhesive to said wedge shaped strips, grouping a full complement of said wedge shaped strips about a common axis to provide a built up shaft and then turning the same to size.

6. The method of making a built up shaft 85 or rod which consists in providing a length of bamboo, removing the nodes therefrom, splitting the same along the grain into strips and removing the diaphragm therefrom, straightening and flattening each strip by a 90 confining pressure, removing one half of each strip along a diagonal plane extending between diametrically opposite corners to provide a strip of wedge shaped cross section with the enamel occupying one tapering side thereof, applying an adhesive to said tapering surfaces and grouping a full complement of such wedge shaped strips about a common axis to provide a built up structure and then turning the same to size. 95

7. The method of making a built up shaft or rod which consists in providing a length of bamboo, removing the nodes from the exterior thereof, splitting it along the grain into strips and removing the diaphragm parts therefrom, impregnating the strips to solidify the fibrous structure thereof, straightening and flattening each strip by a confining pressure making each strip wedge shaped in cross section with the natural enamel on one of the 100 tapering faces thereof, applying an adhesive to each strip, grouping a full complement of such strips about a common axis with all tapering faces arranged radially of said axis to provide a built up shaft and then turning 105 the same to size.

8. The method of making a built up shaft or rod which consists in providing a length of bamboo, removing the nodes from the exterior thereof, splitting it along the grain into strips 110 and removing the diaphragm parts therefrom, impregnating the strips to solidify the fibrous structure thereof, straightening and flattening each strip under a confining pressure, and cutting each strip longitudinally 115 along a plane extending through diagonally opposite corners, thus providing a wedge shaped strip with the natural enamel on one of the tapering faces thereof, applying an adhesive to said strips and grouping a full 120

100

105

110

115

120

125

130

- complement thereof about a common axis with the tapered faces disposed radially of said axis to provide a built up shaft blank and then turning the same to size.
- 5 9. A built up bamboo shaft composed of a plurality of wedge shaped split strips grouped and cemented together about a common axis and having the natural enamel of each strip disposed on one of its tapered faces,
- 10 which faces are radially disposed about said axis.
10. A built up bamboo shaft composed of a plurality of wedge shaped strips grouped about a common axis and cemented together
- 15 with the tapered faces of said strips disposed radially and with the natural enamel of the bamboo forming at least one of such surfaces for each strip.
11. A built up bamboo shaft composed of a plurality of wedge shaped strips grouped about a common axis and cemented together with the tapered faces of said strips disposed radially and with the natural enamel of the bamboo forming at least one of such surfaces for each strip, each strip being impregnated ²⁰ to solidify the fibers thereof.
- In testimony whereof, I have hereunto set my hand, this 3rd day of June, 1927.

THEODOR WENSEL.
